CLAIM

I claim the ornamental design for a battery, substantially as shown and described.

DESCRIPTION

FIG. 1 is a front view of a battery;

FIG. 2 is a bottom view thereof;

FIG. 3 is a top view thereof;

FIG. 4 is a right view thereof;

FIG. 5 is a rear view thereof;

FIG. 6 is a left view thereof; and,

FIG. 7 is a top, right, front perspective view thereof.

The broken lines in the drawings are directed to environment and form no part of the claimed design.
